UNITED STATES PATENT OFFICE.

DOUGLAS E. BONNER, OF NEW YORK, N. Y.

FOLDING TOP.

1,325,187.

Specification of Letters Patent. Patented Dec. 16, 1919.

Application filed March 25, 1913, Serial No. 756,700. Renewed October 4, 1919. Serial No. 323,607.

To all whom it may concern:

Be it known that I, DOUGLAS E. BONNER, a citizen of the United States, and a resident of New York city, county and State of New York, have invented certain new and useful Improvements in Folding Tops, of which the following is a specification.

My invention relates to tops, hoods or covers particularly for use on vehicles of any type, on small boats, and as awnings of any description, and relates more specifically to that type of top, hood or cover which may be raised and lowered or folded at will. The object of my improvement is 15 to construct such tops, hoods or covers in a manner to permit the same to be raised or lowered by one person with substantially no danger of cutting or chafing the covering material. My invention further 20 contemplates the provision of a top, hood or cover which, in a simple manner, may be specially adjusted on a vehicle or other object to overcome variations in the same or to compensate for any stretching or other 25 variation in the different members of the top. Another object of my invention is to provide a structure in which certain of the members composing the top, hood or cover will be compelled to fold simultaneously. 30 My invention will be fully described hereinafter, and the features of novelty will be pointed out in the appended claims.

Reference is to be had to the accompanying drawings in which Figure 1 is a side elevation of one form of my improved top; Fig. 2 is a similar view of another form thereof; Fig. 3 is a similar view showing the latter form of top in a partly folded condition; Figs. 4 and 5 are enlarged views 40 showing details of construction; Fig. 6 is a section on the line 6—6 of Fig. 5 and Fig. 7 is a sectional view on the line 7—7 of Fig. 5.

In the drawings the various forms of 45 my improved top are shown as applied to an automobile, it being understood that this is only an example of one application of my improvement. The rear portion of the top may be of any suitable construction, 50 and as shown, may comprise a main bow 10 and a rear bow 11 pivoted respectively at 12 and 13 to an intermediate bow 14 which latter is pivotally secured at 15 in any suitable manner to the body of the vehicle 16 or other object with which the top is to be

combined. An articulated front or peak bow 17 is pivoted at 18 to the main bow 10 and comprises a front section 19 pivoted to rods 20 by means of rule or break joints 21 capable of breaking only in a downward direction. The customary covering material 22 is stretched over all of the bows and is secured to the vehicle body or other object in any well known and usual way. In the unfolded or raised position of the top, 60 the front bow 17 extends in a horizontal direction over the front of the vehicle or other object and is maintained or suspended in this position by means of a brace 23 having its one end pivotally connected at 24 to the main bow 10 at a point above the pivot 18 and its other end pivotally connected at 25 to the front section 19 of the front bow 17 at a point beyond the joint 21. In the preferred construction, the brace 75 23 is flexible and to this end may comprise a chain, a cable or it may be made of any other suitable flexible material and if desired may be covered with leather or any other suitable material. It is to be understood, however, that in some cases a rigid brace 23 may be found preferable. In order that the front bow 17 may be properly positioned in its unfolded condition, I prefer to provide a suitable means for increasing 80 or decreasing the length of the brace 23 so that the distance between the pivots 24 and 25 may be properly adjusted and the front bow thus properly adjusted over the vehicle or other object. In the illustration the 90 means for accomplishing this result comprises a turn-buckle 26 which co-operates with a screw-threaded bolt 27 located at either end of the brace 23. It will be readily seen that by rotating the turn-buckle 95 26 in one direction or the other to screw it up or down on the bolt 27 the length of the brace 23 may be either decreased or increased and the front bow 17 consequently swung up or down on the pivot 18 until it 100 extends in the desired horizontal direction over the vehicle or other object when unfolded. The adjustment of the turn buckle 26 may be accomplished either by disconnecting the one end of the brace 17 from one of the bows and rotating said turn buckle bodily or simply by rotating a movable part of said turn buckle without disturbing its connection with one of the bows. It will also be apparent that, if desired, a 110

turn buckle or other suitable device may be located at each end of the brace 23, thus providing for a greater range of adjustment than is possible with a single turn buckle or other device. After the length of the brace 23 has been properly adjusted, it may be found that the front bow 17 does not fold properly against the main bow when the top is lowered or that the brace 23 when constructed of flexible materials sags objectionably in the folded condition of the top, instead of remaining substantially taut. To overcome and remedy these objections I provide a plurality of pivot points, 28, 28^a and 28^b on the main bow 10 located at a distance from each other along a line representing an arc of circle which has the pivot 25 substantially for a center, the pivot points being either sockets as shown in which case the pivot 24 comprises a pin adapted for insertion therein or said pivot points comprising pins in which case the pivot 24 would be in the nature of a socket adapted to receive one or the other of said pins. Thus by connecting the pivot 24 with the proper pivot points 28, 28^a and 28^b the inclination or angle of the brace 23 in the unfolded or raised condition of the top is changed without changing the distance between the pivots 24 and 25 and without disturbing the extended position of the front bow 17, this being due to the fact that the pivot points 28, 28^a and 28^b, as before stated are located along a line representing an arc of a circle described substantially about the pivot 25 as a center. In other words, if, when the top is folded with the parts adjusted as in the illustration it is found that the flexible brace 23 sags, or in the case of a rigid brace 23 that the front bow does not fold closely against the main bow, then the pivot 24 is simply disconnected from the intermediate pivot point 28^a and connected with the pivot point 28 thus increasing the distance between the pivots 18 and 24 and in consequence taking up any slack in a flexible brace 23 or permitting the proper operation of a rigid brace to permit proper folding of the top. If it is found that the distance between the pivots 18 and 24 is too great to permit the top to fold properly, then the said pivot 24 may be connected with the pivot point 28^b to overcome the difficulty, it being understood that any number of pivot points may be provided, and further, that the adjustment described may, in some case, be accomplished by similarly shifting the opposite end of the brace 23. In this latter case, the pivot points 28, 28^a and 28^b would be located on the front bow 17 along an arc described about the pivot 24 as a center.

In practice, in assembling the top, considerable difficulty has been experienced to

properly position the pivots corresponding to the pivots 18 and 24 of the front bow and the brace relatively to each other to properly connect said front bow and brace with the main bow and secure a proper co-operation of these elements under all conditions. To overcome this difficulty, I have provided a pivot plate or templet 29 on which the connection for the front bow pivot 18 and the pivot points 28, 28^a and 28^b are produced in accurate position relatively to each other. In assembling the top, this plate 29 is simply secured to the main bow 10 by means of screws or other fastening devices 30 after which the front bow and brace are simply connected at the proper points without any experimenting being necessary to first properly locate the points at which these connections should be made to secure the intended results.

In some cases it may be of advantage to have an intermediate or auxiliary bow included in the top. As shown in Figs. 2, 3 and 4, such auxiliary bow 31 may be pivoted at 32 to the rods 20 and in the extended or raised condition of the top is inclined relatively to the front or peak bow 17 as illustrated best in Figs. 2 and 4. A link 33 is pivotally connected at 34 with the brace 23, and at 35 with the auxiliary bow 31 and serves to connect the said brace 23 and the bow 31 together. It is obvious that link 33 can be located at positions other than shown in the drawings relative to brace 23 and bow 31. In some cases it may be found advantageous to position link 33 substantially parallel to brace 23. This link, in addition to helping to support the auxiliary bow 31 in an inclined position when the top is raised, also compels the said auxiliary bow 31 to swing to a folded position when the top as a whole is lowered or folded. Another object of the link 33 is to increase the leverage with which the auxiliary bow 31 acts on the rod 20, and tending to hold the said rod up when the top is in its raised position. The link 33 further provides a method of attaching the auxiliary bow 31 to the brace 23 and rod 20 whereby said auxiliary bow 31 in addition to a movement in the arc of a circle relatively to said brace 23 can also move bodily toward and away from a straight line drawn through the pivots 24 and 25. In planning tops of the present type it is of decided advantage to be able to attach bow 31 to the rod 20 at a point which is the proper distance from the pivot 18 to best meet the conditions of each individual instance or to position the end of the bow 31 at an equal distance from the bows 10 and 17 when the top is raised, while at the same time getting the preferred angle of inclination in said bow 31 in this position of the top. This may be readily accomplished for instance by means of the

link connection between the brace 23 and bow 31. If the bow 31 and continuous brace 23 were connected by means of an ordinary pivotal connection only a movement in the 5 arc of a circle would be possible in bow 31 relatively to brace 23 and only one dimension between the pivots 18 and 32 and one inclination of the bow 31 would be available in order to secure an operative structure. This is due to the fact that such pivoted connection must of necessity remain 10 in a fixed position relatively to a line drawn through the pivots 24 and 25 both in the open and folded position of the top, as the 15 movement of said bow 31 in such a construction, with respect to said straight line, would be confined solely to a pivotal movement about a relatively fixed point. This would limit the arrangement to certain conditions 20 and would prevent the construction of a satisfactory top when the conditions to be met were different. With the link connection between the brace 23 and bow 31 these objections are obviated and the bow 31 can move 25 bodily toward and away from said straight line through the pivots 24 and 25 thus making it possible to meet all requirements in every case in a satisfactory manner. In order that the said link 33 may properly connect 30 said brace and said auxiliary bow 31 and not interfere with the adjustment of the brace 23 and the proper folding of the top, I prefer to provide the auxiliary bow 31 with a number of pivot sockets or pins 35 36 located along an arc having the pivot 34 as a center and adapted to permit the pivot 35 to be adjusted in much the same manner as is the pivot 24. In other words, after the pivot 24 has been properly adjusted, 40 the pivot 35 of the link 33 is adjusted to correspond and secure the proper coöperation of the auxiliary bow 31 with the remainder of the top. It will, of course, be understood that in some instances the sockets or pins 45 36 may be located on the brace 23 in an arc described about the pivot 35 as a center. It is further to be understood that, while I have described a single brace 23 and link 33 with their coöperating parts, the said 50 brace 23 and link 33 and coöperating parts may be duplicated on each side of the top.

Assuming the top to be in its raised position, and it is desired to lower the same, all that is necessary is to raise and then 55 move rearwardly the forward end of the front bow 17 which movement will break the joint 21 downwardly, the link 33 causing the auxiliary bow 31, if it forms part of the top, to follow and the operation bringing the 60 parts to the position shown in Fig. 3. A continued pressure on the said front bow 17 toward the rear will finally cause the main bow 10, rear bow 11 and intermediate bow 12 to swing rearwardly and downwardly on the pivot 15 to a completely fold-

ed condition. To raise the top a pull is exerted on the front bow 17 which will bring about a reverse operation of the parts and will finally bring the top to the fully raised position shown best in Figs. 1 and 2. In 70 this fully raised position, the usual front straps or other suitable means prevent rearward movement of the top and accidental breaking of the joint 21, while the covering material 22 attached to the rear end of the 75 vehicle body or other object prevents forward movement of the top on the pivot 15. It will be seen that both the raising and lowering of the top may be accomplished in a simple manner by one person without any 80 assistance.

When the brace or braces is or are made of flexible material the said brace or braces will yield transversely if a pressure is exerted thereon and in consequence will not 85 pinch, cut or chafe the covering material 22 in any position of the top. By covering such flexible braces with leather or the like the said covering material 22 is still further protected against injury from said braces. 90

In addition to the above advantage my improvement also provides for the ready and proper adjustment of the various points to secure the best results in the finished top and to compensate for any variation 95 of the parts thereof and also makes it a simple matter to readily and properly connect the front bow and brace with the main bow without first requiring a great deal of experiment to correctly position the points 100 of attachment of these parts.

Various changes in the specific forms shown and described may be made within the scope of the claims without departing from the spirit of my invention. 105

I claim:

1. A folding top or the like comprising a main bow, an articulated front bow pivotally connected with said main bow, an auxiliary bow pivotally secured to said 110 front bow, and a flexible brace pivotally connected with said main bow and said front bow, said flexible brace being further connected with said auxiliary bow so as to permit a movement of the latter relatively 115 to the brace in the direction of the brace's length.

2. A folding top or the like comprising a main bow, an articulated front bow pivotally connected with said main bow, an auxiliary 120 bow pivotally secured to said front bow, a flexible brace connected with said main bow and said front bow for suspending the latter horizontally in its unfolded position and a link connection from said flexible brace to 125 said auxiliary bow for suspending the latter in operative position.

3. A folding top or the like comprising a main bow, an articulated front bow pivotally connected with said main bow, a brace 130

- having one end connected with said front bow and its opposite end connected with said main bow, and coöperating elements on said main bow and said brace whereby the 5 point of connection of the opposite end of said brace may be shifted lengthwise of said main bow.
4. A folding top comprising a main bow provided with a series of apertures arranged 10 lengthwise thereof, an articulated front bow pivotally secured to said main bow, a brace having one end connected with said front bow and a pivot pin on said brace arranged to enter any of said apertures whereby the 15 opposite end of said brace is secured to said main bow and is shiftable lengthwise thereof.
5. A folding top comprising a main bow, a front bow pivotally connected therewith, a 20 brace pivotally connected with said main bow and said front bow and means whereby the pivotal connection between said brace and said main bow may be adjusted substantially in an arc having the pivot at 25 the opposite end of said brace for a center.
6. A folding top comprising a main bow, a front bow pivotally connected therewith, a brace pivotally connected with said main bow and said front bow, means for adjust- 30 ing the length of said brace and means whereby the position of a pivotal connection between said brace and one of said bows may be adjusted in an arc having the pivot at 35 the opposite end of said brace substan- tially as a center.
7. A folding top or the like comprising a main bow, a front bow movably connected therewith, an auxiliary bow movably connected with said front bow and a brace mov- 40 ably connected with said main bow and said front bow, said brace being further connected with said auxiliary bow so as to permit a movement of the latter relatively to said brace in the direction of the brace's length. 45
8. A folding top or the like comprising a main bow, a front bow movably connected therewith, an auxiliary bow movably connected with said front bow, a brace connected with said main bow and said front 50 bow for suspending the latter horizontally in an unfolded condition and a link connection from said brace to said auxiliary bow for suspending the latter in operative position.
9. A folding top comprising a main bow, a front bow pivotally connected therewith, an auxiliary bow pivotally connected with said front bow, a brace having its opposite ends pivotally connected respectively with 55 said main bow and said front bow, a link pivotally connected with said brace and said auxiliary bow respectively and means whereby one of the pivots of said link may be adjusted in an arc having the other pivot 60 substantially for a center.
10. A folding top comprising a main bow, a main front bow pivotally connected therewith, an auxiliary bow pivotally connected with said front bow, a brace having its opposite ends pivotally connected respectively with 70 said main bow and said front bow, means for adjusting the length of said brace, means whereby the position of a pivotal connection between said brace and said main bow may be adjusted in an arc having the pivot at the opposite end of said brace substantially as a center, a link pivotally connected with said brace and said auxiliary bow respectively and means whereby one of the pivots of said link may be adjusted in 75 an arc having the opposite pivot substantially for a center.
11. In a vehicle top the combination of a main bow, a front bow connected therewith, a brace connected with said main bow and 80 said front bow, and an auxiliary bow connected with said brace and said front bow, one of said connections permitting a relative movement of the elements which it connects toward and away from each other. 85
12. In a vehicle top the combination of a main bow, a front bow, two members comprising a rod and a brace each having one end pivotally connected with said main bow and the other end pivotally connected with 90 said front bow, an auxiliary bow pivotally connected with one of said members and a link pivotally connected with said auxiliary bow and with the other member.
13. A folding top comprising a main bow, 100 an articulated front bow hinged thereto, a brace pivoted to said main bow and to said front bow, an auxiliary bow hinged to said front bow and means coöperating with said auxiliary bow and said brace and permitting 105 a movement of the auxiliary bow in a direction transverse to a straight line between the brace pivots.
14. A folding top comprising a main bow, a front bow hinged thereto, a brace pivoted to said main bow and to said front bow, an auxiliary bow hinged to said front bow, and means coöperating with said auxiliary bow and said brace for permitting a progressive movement of the auxiliary bow to- 110 ward and away from a line passing through said brace pivots.
15. A vehicle top comprising a main bow, a front bow, a link pivoted to each side of the front bow, and to the main bow, a brace pivoted to the side of the main bow above the link and to the front bow in front of the pivot thereof, an intermediate bow pivoted to the brace, and means connecting the intermediate bow and the link for moving the intermediate bow during the opening and closing of the top. 120
16. A vehicle top comprising a rear bow, an arm pivoted thereto, an outrigger bow, a stop hinge for pivotally connecting the 125

outrigger bow to the arm, an auxiliary bow pivoted to the arm, a brace fulcrumed to the rear bow and to the outrigger bow, and a pivot joint that connects the auxiliary bow to the brace, whereby a tension is exerted upon the stop hinge which sustains the top against collapsing.

In testimony whereof I have hereunto set my hand in the presence of two subscribing witnesses.
